(57) CLAIM

The ornamental design for a door of clothing caring unit having ironing device, as shown and described.

DESCRIPTION

FIG. 1 illustrates a front top perspective view of the door of clothing caring unit having ironing device showing our new design;

FIG. 2 illustrates a front elevational view thereof;

FIG. 3 illustrates a rear elevational view thereof;

FIG. 4 illustrates a left side elevational view thereof;

FIG. 5 illustrates a right side elevational view thereof;

FIG. 6 illustrates a top plan view thereof; and,

FIG. 7 illustrates a bottom plan view thereof.

The broken lines shown throughout the views depict unclaimed portions of the design and form no part of the claimed design.
